Patented Dec. 12, 1922.

FIG. 1.

FIG. 2.

FIG. 3.

INVENTOR:

William G. Punnell
BY A. M. Carlson
ATTORNEY.

UNITED STATES PATENT OFFICE.

WILLIAM G. PUNNELL, OF ST. PAUL, MINNESOTA.

CHILD'S VEHICLE.

Application filed February 23, 1922. Serial No. 538,470.

To all whom it may concern:

Be it known that I, WILLIAM G. PUNNELL, a citizen of the United States, residing at St. Paul, in the county of Ramsey and State of Minnesota, have invented a new and useful Child's Vehicle, of which the following is a specification.

My invention relates to toys, and more particularly to wheeled toys of the class adapted to be propelled by one or both feet of the user.

The object of the invention is to provide a toy of unique form and novel and economical construction.

15 In the accompanying drawing:

Fig. 1 is a top view of my improved toy.

Fig. 2 is a left side elevation of Fig. 1.

Fig. 3 is a front elevation of the toy.

20 Referring to the drawing by reference numerals I have illustrated a child's vehicle resembling a bi-plane mounted on two small front wheels 4 in caster forks 5, and two rear wheels 6 rotatably secured to a transverse, vertical rear bolster 7. The casters have 25 their shanks pivotally engaged in opposite ends of an inverted T-shaped bolster 8 which has its leg 8^a projecting upward in about vertical position and its upper end secured to the upper end of a longitudinal, rearwardly and downwardly inclined main frame bar 9, the latter also being secured, near its rear end, to the upper part of the rear bolster 7. A lower longitudinal frame bar 10 arranged in almost horizontal plane, 30 holds the front and rear bolsters in proper spaced relation.

Near the front and upper end of the main frame bar 9 I secure a number of transverse bars 11, preferably made of thin boards, and 35 resembling the wings of an airplane, and at the rear lower end of said bar I secure another transversely arranged board 12, tapered toward its outer ends to resemble

the tail of an airplane and preferably made of the same material as the bars or wings 11. 45

Intermediate the bars 11 and 12 I place a seat 13, which has its front end secured to the main frame bar 9 and its rear portion secured to a vertical transversely arranged board 14 mounted on the said bar 9 and serving as a back rest and guard.

A child using this toy simply sits on seat 13 with the legs straddling the frame bar 9, the hands resting on the wings 11, and propels the toy forward or backward by making kicking strokes on the ground with the feet. Steering is easily accomplished by pushing to the right or left, by the feet on the ground or the hands on the wings 11, as the offset casters 5 will swerve in the direction of the push, and the casters will naturally be directed accordingly.

55 The toy, as described, is not only a means providing exercise for children but has the feature of easy steering and the novelty of 60 appearing to ride in an airplane.

Having thus described my invention what I claim is:

1. In a toy of the class described a front bolster with two casters supporting it, a rear bolster with a ground wheel at each end, a longitudinal frame bar connecting the two bolsters, a body bar secured upon the two bolsters and inclining upwardly with its front end, said inclined bar having a seat 75 for the operator and forward thereof transverse handles resembling the wings of an airplane and rearward of the seat an extension resembling the tail of an airplane, said inclined bar projecting forward of the front 80 bolster and rearward of the rear bolster.

2. The structure specified in claim 1, in which said frame bar is also inclined upwardly at its front end.

In testimony whereof I affix my signature, 58
WILLIAM G. PUNNELL.
